COMBINED DISPENSING AND MEASURING DEVICE FOR GUNPOWDER

Henry W. Lachmiller, Los Angeles, and James G. Bell,
Glendale, Calif., assignors to Lachmiller Engineering
Co., Glendale, Calif., a corporation of California

Application March 21, 1955, Serial No. 35,130

Term of patent 14 years

(Cl. D52—2)

Fig. 1 is a front elevational view of a combined dispensing and measuring device for gunpowder showing our new design;

Fig. 2 is a side elevational view;

Fig. 3 is a rear elevational view;

Fig. 4 is a top plan view; and

Fig. 5 is a bottom plan view.

The characteristic features of the design reside in the solid line portions.

We claim:

The ornamental design for a combined dispensing and measuring device for gunpowder, as shown and described.
